COP WINDING MACHINE WITH INDEPENDENT WINDING POINTS

Wilhelm Reiners, Walter Reiners, and Gustav Kahlisch, Gladbach-Rheydt, Germany, assignors to W. Schlafhorst & Co., Gladbach-Rheydt, Germany, a corporation of Germany

Application May 13, 1939, Serial No. 273,478
In Germany May 20, 1938

4 Claims. (Cl. 242—35.5)

The invention relates to cop winding machines with independent winding units, on which the thread is wound on a tube and when the cop is finished the ejection of the cop and severance of the thread take place automatically. It has already been proposed in arrangements of this type, in our copending application, Ser. No. 71,266, filed March 27, 1936, to supply the winding stations with empty tubes automatically, using an endless circulating conveying means which automatically supplies the tubes to individual magazines each coordinated with a winding unit, together with transfer devices which deliver the tubes from the magazines to the winding units.

This idea is improved upon according to the invention in the sense that, omitting the magazines, grippers controlled by the actuating gear of each winding unit are provided, which grippers automatically take up the empty tubes from conveying means preferably arranged below the winding spindles, and operate in synchronism with the work at each winding unit to transfer an empty tube to each spindle from which a cop has been doffed.

The invention is illustrated in the accompanying drawing, in which:

Fig. 1 shows in front elevation, partly in section on line I—I of Fig. 2, four winding points (a—d) of a coppering rail with the empty tube grippers in different positions.

Fig. 2 shows a single winding point and conveyor chain in top plan view.

Fig. 3 shows a special arrangement at the reversal point opposite the feeding point of the conveyor chain.

The conveyor chain 1 is driven in the usual manner by means of a shaft 2 and sprocket wheels 6, 7. Every other chain link on each side 40 is formed with a rest 3, 4 having a notch 50 to provide troughs for the reception of empty tubes. The outer edges of the rests 3, 4 are so shaped that, as they run under a magazine 5, they always catch the lowermost tube and push it into the 45 notches 50.

The winding machine has any desired number of winding units, only four of which are shown in the drawing at a, b, c, d, respectively, Fig. 1. Each comprises a winding spindle 9 mounted in a 50 gear box 8. The details of the driving and supporting head for the tubes are generally known and therefore not shown. The gear box 8 also accommodates a rock shaft 10, whose rocking movement is controlled by the control gear in the 55 gear box of the winding unit with which it is

associated, in the manner required by the oscillating movement of levers 11, 12 fixed to shaft 10, as hereinafter described. Bell crank levers 14, 22 are oscillatable about pins 13 on the levers 11, 12, their movement being limited by stop pins 23, 5 24. The arms 14 of the bell crank levers 14, 22 are connected by a cross bar 15. The front end of each of the arms 14 is constructed as a gripper trough 16. Cover fingers 19, oscillatable on a common shaft 17, serve for closing the gripper troughs 16 and are maintained in closing position under the influence of a spring 18. The shaft 17 has at one end a lug 20, which in the position shown at winding unit a in Fig. 1 strikes against a stop 21 fixed on the gear box, with the result 15 that the gripper trough 16 is opened by raising the fingers 19 against the action of the spring 18.

The shaft 10 and levers 11, 12 fixed thereto constitute a rocking frame, while the bell crank levers 14, 22, tied together by cross bar 15 and 20 formed with gripper troughs 16 constitute a holder frame, the two frames together forming a transfer device for transferring tubes from the conveyor 1 to the spindles 9. The transfer device moves between the three positions shown in 25 Fig. 1 at the winding units a, b, and c, the transfer device at unit d being in the same position as at unit b, with the exception of one of its controlling elements to be described presently. The position at winding unit a is the receiving position, at which the transfer device is supplied with 30 a tube from the conveyor 1. The position at unit b is the intermediate position, at which the transfer device, supplied with a tube, waits for the previous cop to be completed and doffed, before 35 moving to the donning position, which is shown at unit c. On its return movement the transfer device goes first to the intermediate position shown at unit d and is then restored to receiving position, shown at unit a. The movements from 40 receiving position to intermediate position and from intermediate position to receiving position are executed by the holder frame alone and are produced by the coaction of the conveyor with the transfer device. The movements from intermediate position to donning position and back to intermediate position are executed by the holder frame and the rocking frame swinging together on their pivotal connection with the winding unit and are produced by the control gear of the winding unit. To carry out these movements of the transfer device the following mechanism is provided:

A pin 25 is rotatably mounted on the free end of the arm 22 of the inner bell crank lever 14, 22, 55

and through this pin a rod 28 extends, which is fixed on a bolt 27 of a small lever 28, forming therewith a bell crank lever. This rod 28 is slidably guided in the pin 25. A spring 29 is slipped on to the rod 28 between the pin 25 and the bolt 27 and tends to press these two parts apart. The bolt 27 in turn is mounted on the end of a lever 30 oscillatable about a pin 31, the movement of the lever being limited by abutment pins 32, 33.

10 The lever 28 carries on its free end a small abutment plate 34 and the lever 14 an abutment plate 35. These abutment plates, when the transfer device is in certain positions, can come into contact, respectively, with control abutments 15 36, 37 on the conveyor chain 1. An abutment 38 is further provided on the gear box 8 to limit the swinging movement of the lever 11 in upward direction.

10 The operation of the device will be explained 20 by reference to the four successive positions shown at the winding units a, b, c, d, in Fig. 1. When a transfer device is waiting to receive a cop tube from the conveyor 1, it stands in the receiving position shown at a. The abutment plates 34 25 and 35 are both out of the planes of abutments 36 and 37 and no action takes place until a tube rest 3, 4 brings a tube H to the gripper jaws 16, which stand uncovered by fingers 19 ready to receive the tube. The action is commenced by the 30 entrance of a tube into the gripper jaws 16, which results in pressing the levers 14 slightly forwards as the chain 1 moves on. This raises the pin 25 and turns the bell crank lever 28, 28 so that the abutment plate 35 comes into the path of the 35 control abutment 37 on the conveyor chain 1. This movement is therefore only possible when a tube and not when a chain link without tube comes into the range of the gripper trough 16. The plate 35 is in turn pushed forwards by the 40 abutment 37, with the result that the lever 14 moves into its vertical position and the transfer device assumes the intermediate position shown at winding unit b. The bolt 27 all this time is in its upper position determined by the pin 32 and 45 the abutment plate 34 remains above the level of control abutments 36.

As soon as the work at the winding unit is 50 terminated and the finished cop is ejected by the control gear, the gear, through the intermediary of a friction clutch (not shown), causes the levers 11, 12 to move upwards until the lever 11 and bolt 27 strike against the abutment 38, the bolt 27 being at the same time pressed into the position limited by the pin 33 where it is held 55 by spring 29, as shown at winding unit c. In this position, which is the donning position, the empty tube is between the driving head and the counter supporting head of the winding spindle 9 and is gripped thereby in the usual manner and 60 retained when the levers 11, 12 descend. As the levers 11, 12 return to the intermediate position once more, as shown at the winding unit d, the plate 34, owing to the lowered position of lever 30, comes under the chain 1 and consequently into 65 the range of the abutments 36. During the feed of the chain 1 the bell crank lever 28, 28 swings, under the action of the abutment 36, with the result that the pin 25 is depressed and the levers 14, together with the gripper trough 16, are again 70 brought into the receiving position shown at a.

The finished cops ejected from the winding units are guided in the usual manner over guide plates to collecting receptacles or conveyor bands for full bobbins.

75 The feeding speed of the chain 1 is so calcu-

lated that in a unit of time more empty tubes are supplied than are required by all the winding units. To carry along the excess number of tubes over the turning point at the end of the coppering rail, retainers in the form of hooks 48 5 (Fig. 3), pivoted by pins 47 on the chain links carrying tube rests 3, 4, are provided to engage the undelivered tubes at the end of the conveyor and hold them to the tube rests. Each hook 48 has a finger 45, into the path of which projects a 10 pin 44 on a boss 43 of a ring 42 secured to stationary sprocket shaft 41. The pin 44 throws each hook 48 as it reaches the end of the conveyor, into position to engage and hold any tube remaining on the tube rest. A pin 49 on hook 15 48 is provided to engage a lug (not shown) at the left end of the conveyor, to release the tube before it reaches the first transfer device.

What we claim as our invention and desire to secure by Letters Patent of the United States is: 20

1. In combination with a winding unit including a spindle adapted to wind cops on tubes, tube-supplying means comprising a transfer device; a conveyor having means for carrying tubes to said transfer device; said transfer device being movable between three main positions, namely, receiving position, intermediate position and tube-donning position; means whereby said conveyor moves said transfer device from receiving position to intermediate position on supplying a tube 30 thereto; means operable by the winding unit for moving said transfer device from intermediate to donning position, and back to intermediate position; and means whereby said conveyor moves the transfer device, after its return to intermediate position from intermediate position to receiving position. 35

2. A mechanism as described in claim 1, wherein said means whereby said conveyor moves said transfer device from receiving position to intermediate position comprises abutment members on said conveyor and said transfer device normally in non-coacting position when said transfer device is in receiving position, and means whereby one of said abutment members is moved into coacting position by the engagement of a tube carried by said conveyor with said transfer device. 40

3. A mechanism as described in claim 1, wherein said transfer device comprises a rocking frame pivotally connected to said winding unit and a holder frame articulated to said rocking frame, the movement of said transfer device between receiving position and intermediate position being a rocking movement of said holder frame on said rocking frame, and the movement of said transfer device from intermediate position to donning position and back to intermediate position being a rocking movement of both said frames together about the pivotal connection of said rocking frame to said winding unit. 55

4. In combination with a winding unit including a spindle adapted to wind cops on tubes, tube-supplying means comprising a transfer device; a conveyor having means for carrying tubes to said transfer device; said transfer device being movable between three main positions, namely, receiving position, intermediate position and tube-donning position; means whereby said conveyor moves said transfer device from receiving position to intermediate position on supplying a tube thereto; means operable by the winding unit for moving said transfer device from intermediate to donning position, and back to intermediate position; means including abutment members on 70 75

2,236,300

5 said conveyor and said transfer device for moving the transfer device, after its return to intermediate position, from intermediate position to receiving position; said abutment members being normally in non-coacting position when said transfer device has moved from receiving position to intermediate position; and means whereby one of the said abutment members is shifted during the

movement of said transfer device by said winding unit, in order to bring said abutment members into coacting relation upon the return of said transfer device from donning position to intermediate position.
